UNITED STATES PATENT OFFICE.

CARL GEORG BRACKLOW, HERMANN GUSTAV EUGEN TIMM, AND HEINRICH BÜNZ, OF NEUMINSTER, GERMANY.

SMOKE-CONSUMING APPARATUS FOR FURNACES OR BOILERS.

SPECIFICATION forming part of Letters Patent No. 731,015, dated June 16, 1903.

Application filed June 23, 1902. Serial No. 112,943. (No model.)

To all whom it may concern:

Be it known that we, CARL GEORG BRACKLOW, HERMANN GUSTAV EUGEN TIMM, and HEINRICH BÜNZ, subjects of the German Emperor, residing at Neumünster, Holstein, Germany, have invented certain new and useful Improvements in Smoke-Consuming Apparatus for Boilers or Furnaces, of which the following is a specification.

10 The present invention relates to a smoke-consuming apparatus for furnaces or boilers.

In the annexed drawings, Figure 1 is a longitudinal section illustrating the arrangement of the apparatus in the flame-tube of a steam-boiler. Fig. 2 is a rear view of the apparatus with the damper omitted, and Fig. 3 is a plan view of the apparatus in section on the line *x-x* of Fig. 1.

The apparatus consists in the main of the 20 hollow hood *b*, which rests on a base-plate *a* and serves at the same time as a fire-bridge. This hood is open at the rear and is adapted to be closed by a damper *d*, pivoted to said base-plate and operated by means of a rod *c* 25 brought to the front or foot plate. The characteristic feature of the apparatus is that the outflow of heated air from the apparatus, and not, as was hitherto almost universally usual, the supply of fresh air to the latter, is regulated at will.

The hollow hood or bridge *b* and damper *d* are provided with several intermeshing ribs *e*, by which the cold air entering freely at the bottom and impinging on them is heated, 35 while at the inner edge of the hood, which edge is divided into small recesses, a perforated steam-pipe *g* is provided, from the perforations *i* of which (each of which leads to one recess of the edge) steam is emitted in 40 jets and moistens the heated air leaving the apparatus or mixes with the said air and the departing smoke gases.

The outflowing steam, by which the upper edge of the hollow body *b* is continuously 45 moistened at the same time, and thus prevented from burning, has also the purpose of imparting to the air leaving the apparatus a considerably-increased speed, even with the most unfavorable conditions of draft and the 50 damper *d* almost closed, whereby a possible

return of the fresh air to the apparatus is avoided.

By the jet-like continuous action of the steam upon the simultaneous outflowing hot air a gaseous mixture is produced which effects the energetic and complete combustion of all the combustible residue contained in the departing motor-gases, so that the latter actually leave the uptake free from smoke.

We declare that what we claim is—

1. In smoke-consuming apparatus for boilers and furnaces, the combination of a hood open at the rear, and adapted to serve as a fire-bridge, a damper adapted to close said hood, means for operating said damper, and 65 a plurality of intermeshing ribs on said hood and damper respectively, substantially as described for the purpose set forth.

2. In smoke-consuming apparatus for boilers and furnaces, the combination of a hood open at the rear, and adapted to serve as a fire-bridge, a pivoted damper adapted to close said hood, means for operating said damper from the front of the boiler or furnace, and a plurality of intermeshing ribs on said hood and damper respectively, substantially as described for the purpose set forth.

3. In smoke-consuming apparatus for boilers and furnaces, the combination of a hood open at the rear and adapted to serve as a fire-bridge, a damper adapted to close said hood, means for operating said damper, a plurality of intermeshing ribs on said hood and damper respectively, and means for admittance of steam to said hood for moistening the outflowing air and accelerating its speed substantially as described.

4. In smoke-consuming apparatus for boilers and furnaces, the combination of a hood open at the rear, and adapted to serve as a fire-bridge, the edge of said hood having a number of recesses, a damper adapted to close said hood, means for operating said damper, a plurality of intermeshing ribs on said hood and damper respectively and a perforated steam-pipe adjacent the edge of the hood, the perforations in said pipe being each opposite one of said recesses, substantially as described for the purpose set forth.

5. In smoke-consuming apparatus for boil-

ers and furnaces, the combination of a hood open at the rear and adapted to serve as a fire-bridge, the edge of said hood having a number of recesses, a pivoted damper adapted to close said hood, means for operating said damper from the front of the boiler or furnace, a plurality of intermeshing ribs on said hood and damper respectively, and a perforated steam-pipe adjacent the edge of the hood, the perforations in said pipe being each opposite one of

the said recesses, substantially as described for the purpose set forth.

In witness whereof we have signed this specification in the presence of two witnesses.

CARL GEORG BRACKLOW.
HERMANN GUSTAV EUGEN TIMM.
HEINR'CH BÜNZ.
